tion, New York, N. Y., a corporation of New
York

Application October 4, 1935, Serial No. 43,538
In Great Britain October 23, 1934

5 Claims. (Cl. 101—96)

This invention relates to printing mechanism arranged for control by record cards of the kind in which each column is divided into two parts and in which some of the characters which are to be printed are represented each by a single hole in the column and others are represented by pairs of holes, one hole being in one part of the column and the other hole in the other part of the column in accordance with a code. Each column may be conveniently divided into a main part comprising ten hole positions and a subordinate part comprising two hole positions, so that any one of thirty-two characters can be represented in a column. 5 For convenience it will be assumed that the characters are represented on the card by holes punched therein, but the present invention is also applicable to printing mechanism in which the characters are represented by marks made on the card in selected positions and which are read by light-sensitive devices in a known manner. 10

More specifically the present invention relates to printing mechanism of the kind comprising two controlling members which are reciprocated and which are each arrested, as they move from a home position, in a position determined by the position of a hole in an associated part of a column of the card. The two controlling members are arrested by means controlled by a card-reading device and jointly determine the position of a setting member in accordance with the positions in which they are arrested. The setting member serves to position a type-carrier which is provided with type for printing the various characters. One of the controlling members operates to make a coarse adjustment of the setting member and, therefore, of the type-carrier, while the other operates to effect a fine adjustment by moving the setting member relatively to the first controlling member through one or more units of movement which are smaller than the units of movement imparted to the setting member by the first controlling member. 15

It has been proposed to provide means for locking the setting member to the first controlling member in any one of a number of positions and to employ the second controlling member to determine the position in which the setting member will be locked to the first controlling member, the setting member moving with the first controlling member when the latter is adjusted. It has also been proposed to connect the two controlling members to the setting member by differential gearing so that they jointly deter- 20

mine the position of the setting member. Hitherto in mechanism of this kind, the type-carrier has been secured to the setting member. Owing to the large number of type to be accommodated on the type-carrier, the latter has to be of relatively large dimensions and to have a relatively large stroke. The stroke and dimensions of the setting member will be correspondingly large and the stroke of the first controlling member will be at least as large. If the controlling members are connected to the setting member by differential gearing the stroke of the first controlling member will be larger than that of the setting member. 5

It is desirable to keep the strokes of the various parts of the mechanism as short as possible and also the dimensions of the parts, which are partly dependent on their stroke, as small as possible, in order to reduce the inertia effects and allow of the mechanism being operated at a high speed. Further any reduction in the dimensions of the parts is advantageous since it tends towards a compact structure. It will be obvious that the stroke of the type-carrier cannot be reduced since it is determined by the number of type it carries, but it is the object of the present invention to provide printing mechanism of the above kind wherein the stroke and dimensions of the various parts, other than the type-carrier, are reduced as compared with prior mechanism of this kind. 15 20 25

The present invention provides printing mechanism of the above kind wherein the setting member is connected to the type-carrier by movement-increasing gearing so that the stroke of the setting member is less than that of the type-carrier and the controlling members have correspondingly reduced strokes. 30 35

Preferably, the two controlling members are connected to the setting member by differential mechanism which may comprise a differential lever fulcrumed on the two controlling members or parts moved thereby and having the setting member pivoted on it. 40

Conveniently the type-carrier is in the form of a wheel to which a pinion is secured and this pinion meshes with teeth formed on the setting member which is mounted to reciprocate substantially in a straight line. 45

With the arrangement according to this invention, any error in the adjustment of the setting member is magnified in the adjustment of the type-carrier. It is accordingly another object of the present invention to provide the type-carrier with a set of teeth and to provide a justifying 50 55

element movable after the type-carrier has been set to engage between a pair of teeth and accurately position the type-carrier.

The printing mechanism according to the present invention may be employed in combination with the printing mechanism adapted to print numerals only and of the known kind comprising a plurality of reciprocating type-bars and means for differentially arresting them under the control of a record card. According to this feature of the invention the first controlling members are designed to have substantially the same stroke as the type-bars of the numeral printing mechanism and common means is provided for reciprocating the first controlling members and the numeral printing type-bars.

Printing mechanism embodying the above and other features of the present invention will now be described with reference to the accompanying drawings in which:—

Figure 1 is a cross-section through the printing mechanism showing the parts in their normal home position.

Figure 2 is a similar section to Figure 1 but shows the parts in the position occupied at the moment of printing.

Figure 3 shows diagrammatically driving mechanism for the printing mechanism.

Figure 4 is a simplified circuit diagram for the printing mechanism, and

Figures 5 and 6 illustrate the manner in which printing is effected.

Like reference characters indicate like parts in all the figures of the drawings.

Alphabetical and numeral printing mechanism according to the present invention will be described as applied to a record-card-controlled statistical machine of the well-known Hollerith kind such as that shown in U. S. patent to C. D. Lake et al. #1,976,617 dated October 9, 1934. The printing mechanism is provided in addition to the usual printing mechanism which prints numerals only. Since the construction and operation of this kind of statistical machine and of the numeral printing mechanism provided in it are well-known, they will not be described herein.

Referring to Figure 3, the machine is provided with a list shaft 10 (corresponding to list shaft 165 in the above mentioned patent) on which a list cam 11 is rotatably mounted. This cam can be coupled to the shaft 10 by a one-revolution clutch of conventional construction so that this cam operates whenever the clutch is engaged. The clutch is engaged in any cycle of the machine, in which the printing mechanism is to operate, in a well-known manner which need not be described. A gear-wheel 12 is secured to the cam 11 and drives a gear-wheel 13 secured to a shaft 14. This shaft, through bevel gearing 15, drives a shaft 16 which through bevel gearing 17 drives a shaft 18. The shaft 18 thus rotates at such times as the cam 11 is rotating and serves, as will be explained hereinafter, to operate the alphabetical section of the printing mechanism in conjunction with the cam 11.

The cam 11, through a suitable lever not shown, reciprocates a cross-head 20 on guides 21 which are mounted in fixed frame members 22. A plurality of first controlling racks 23 are supported in the cross-head 20. The lower ends of these racks are guided in slots in a cross-bar 24 and the upper ends in slots in the upper frame member 22. Lugs 25 on the lower end of the racks 23 are held against the cross-member 24 by levers 26 which are pivoted in a bracket 27

and are pulled upwardly by springs 28. Thus, as the cross-head rises, the racks 23 will also rise. Each of the racks can be arrested in any position, as it rises, by energizing a rear print magnet RPM. When energized, this magnet rocks a latch 29 to unlatch a pawl 30 which engages one of ten teeth 31 on the rack. The rack is then held while the cross-head continues its upward movement, the springs 28 stretching to permit this.

The cross-head 20 also carries a plurality of type-bars in the numeral section of the printing mechanism. These type-bars are of conventional construction and are similar to the racks 23 except that they are extended upwardly to the level of a platen 32. Each type-bar carries a type-head at its upper end. The type-bars are arrested in the same way as the controlling racks 23 by pawls 30 which are released when the print magnets are energized. As this printing mechanism is well-known it need not be described in detail. Suitable mechanism, not shown, is provided for relatching the pawls 30 behind the latches 29 when the cross-head 20 moves downwards towards its home position. As this mechanism is well-known and has no part in the present invention, it will not be described.

The shaft 18 rotates whenever the cam 11 rotates and the printing mechanism is in operation, as previously explained. This shaft carries a pair of complementary cams 33 and 34 which rock a double-armed lever 35 secured on a shaft 36. A pair of levers 37 are secured on the shaft 36 and engage, at their upper ends, a cross-head 38. The cross-head 38 is supported on guide rods 39 which, in turn, are carried by frame members 40. The timing is such that the levers 35 and 37 and the cross-head 38 remain stationary during the first part of the upward movement of the cross-head 20. During approximately the last third of the upward movement of the cross-head 20, the levers 35 and 37 are rocked counter-clockwise and move the cross-head 38 to the left into the position shown in Figure 2. The two cross-heads are restored simultaneously from the position shown in Figure 2 to that shown in Figure 1.

A plurality of second controlling racks 41 are supported at one end in slots formed in a member 42 which forms part of the cross-head 48. At their other ends the racks 41 are supported in slots formed in a fixed frame member 43. The racks 41 are pressed to the left so that lugs 44 on them engage the member 42 by levers 45. These levers are pivoted in a bracket 46 and pulled to the left by springs 47. The racks 41 will thus move with the cross-head 38 to the left but can be individually arrested, the springs 47 yielding so that the cross-head can continue its movement without the racks.

Each of the racks 41 can be arrested in either of two positions by energizing an associated front print magnet FPM which then rocks a latch 48 to release a pawl 49. This pawl engages one or other of two teeth labelled X and Y in Figure 1, depending on the time when the magnet was energized. The pawl 49 is relatched by a high tooth 50 when the cross-head 38 moves back into the position shown in Figure 1.

If one of the magnets FPM is not energized, the corresponding rack 41 moves to the left until it engages an adjustable stop 51 as shown in Figure 2. The second controlling rack 41 can thus be arrested in any one of three positions as it moves to the left. If one of the magnets

RPM is not energized, the associated rack 23 moves until engaged by an adjustable stop 52. Each rack 23 can thus be arrested in any one of ten positions by energizing its magnet RPM at the appropriate time and in an eleventh position, if this magnet is not energized.

The standard Hollerith record-card has twelve hole positions in a column. The hole positions are designated Y, X, 0, 1 . . . 8 and 9, reading from top to bottom. Each column may be regarded as being divided into two parts, the upper part comprising the "X" and "Y" positions and the lower part the "0" to "9" positions. Each of the magnets RPM is energized at a time determined by the position of a hole in the lower part of a column while the corresponding magnet FPM is energized in accordance with the position of a hole in the upper part of the column.

The numerals and the letters of the alphabet are represented by holes in accordance with the following code:—

-	0	1	2	3	4	5	6	7	8	9
25 X	A	B	C	D	E	F	H	J	K	L
Y	Z	N	P	Q	R	T	U	V	W	X
-	.	0	1	2	3	4	5	6	7	8
30	0	1			G			S		

There is no hole in either the "X" or "Y" positions. A hole in one of the positions "0" to "9" represents the corresponding digit, as shown in the lowest line of the above table. Holes in the "0", "1", "6" and "8" positions may, however, represent the letters O, I, G and S, respectively, the printing mechanism being provided with special type for this purpose. A hole in the "X" position represents A in absence of a hole in one of the "0" to "9" positions and one of the letters B to M if there is a hole in one of the "0" to "9" positions, as shown in the top line of the above table. In the same way, a hole in the "Y" position represents one of the letters in the second line in accordance with the position of the hole in the lower part of the column.

Referring again to Figure 1, each pair of first and second controlling racks 23 and 41 controls the position of a setting rack 53. This rack is pivoted at 54 on a differential lever 55 which is fulcrumed at 56 on the associated first controlling rack 23. The lever 55 carries a pin 56 which rides in a slot 57 in a lever 58 which is pivoted at 59. The associated second rack 41 carries a pin 60 which engages a slot 61 in a lever 62. This lever is also pivoted at 59 and is adjustably secured at 63 to the associated lever 58.

The rack 53 is provided with teeth 64 which mesh with a pinion 65 secured to a type-wheel 66. Each pinion 65 and the associated type-wheel 66 rotate on an individual bushing 67 which is non-rotatably supported on a bar 68. The type-wheel 66 is provided with thirty-three type round one half of its periphery. The type are arranged in the order shown in the above table, starting at A and reading down each column in turn. Thus the type reads A, Z, " ", B, N, O, etc., the "A" type being to the left of the wheel as seen in Figure 1. As the first controlling rack 23 rises, the differential lever 55 rocks about its pivot 56 and raises the setting rack 53 which rotates the type-wheel 66. The arrangement is such that a movement of the rack 23 equal to the pitch of the teeth 31 turns the wheel 66 to carry three of the type past a platen.

Each of the teeth 31 corresponds to one of the digits 0 to 9 and when the rack 23 is arrested by the pawl 30 engaging one of the teeth 31, the corresponding type-wheel 66 will be arrested in a position determined by the position in which the rack was arrested. Since each tooth 31 corresponds to a digit it also corresponds to one of the type on the wheel 66. The arrangement is such that when the rack 23 is arrested, by the pawl 30 engaging a particular tooth 31, say the "5" tooth, the wheel 66 is positioned with the type for printing the next lower digit, for example, in the case suggested, the "4" type, approximately opposite the platen 32.

Concurrently with the latter part of the movement of the cross-head 20, the second controlling racks 41 are moved to the left until arrested by the pawls 49 or by the stops 51. As each rack moves, it rocks the composite lever 58, 62 and rocks the differential lever 55 about its pivot 56 on the associated rack 23. As the lever 55 rocks about its pivot 56 it draws the setting rack 53 downwardly. The rack 53 then rotates the associated type-wheel 66 backwardly. The arrangement is such that if a rack 41 moves its full stroke to the left, it will rotate the wheel 66 through approximately three type spaces. Since each rack 41 can be arrested in any one of three positions, it can rotate the associated wheel 66 backwardly through one, two or three type spaces so as to bring opposite the platen 32 one of the three type immediately following, in a clockwise direction, the type which was positioned opposite the platen 32 by the associated first controlling rack 23.

Each first controlling rack 23 thus effects a coarse adjustment of the associated type-wheel 66 while the corresponding second controlling rack 41 effects a fine adjustment by turning the wheel backwardly one, two or three steps.

Assuming that the slot 57 is horizontal the pivot 54 would move vertically with equal steps as the rack 23 moved up with equal steps. The pivot 54 would also move first to the left and then to the right along a curved path, as the lever 55 turns about its pivot 56. Since the pivot 54 is to the right of the vertical through the point at which the rack 53 meshes with the pinion, the movement of the pivot 54 to the left will accelerate the clockwise rotational movement imparted to the wheel 66 by the setting rack 53 and movement of the pivot 54 to the right will decelerate the movement of the wheel.

There is thus a tendency for the ratio between the speeds of the rack 23 and wheel 66 to decrease as the rack rises. This tendency is overcome by the fact that the slot 57 is normally inclined as shown in Figure 1. As the pivot 54 moves to the left, the pin 56 moves to the left down the slot 57 and is depressed proportionally, decelerating the movement imparted to the wheel. When the pivot 54 and the pin 56 move to the right, the pin is raised by the slot and the movement of the wheel is accelerated. The slope of the slot is selected to provide approximately the required compensation.

A similar effect occurs when the lever 58, 62 rocks, but here movement of the pin 56 to the left in the slot 57 occurs when the movement given to the wheel 66 is decreased and to the right when the movement is increased. The slot 57 is non-radial with respect to the pivot 59 of the arm 58, so that movement of the pin 56 to the left increases the movement imparted to the lever 55 and hence to the wheel 66, while move-

ment to the right decreases the movement imparted to the wheel.

The shaft 68 is supported in a frame comprising a pair of arms 70 pivoted at 71 and connected together at their upper ends by a bar 72. The frame is held against adjustable stops 73 by springs 74. Each of the setting racks 53 is held against its pinion 65 by an individual spring-loaded plunger 75, the plunger 75 being carried in a suitable spring-box 76 which is secured to the bar 72. After all the wheels 66 have been positioned, the frame 70, 72 is rocked about its pivot 71 by a pair of cam elements 77 which are secured on wheels 78 and which engage projections 79 on the arms 70 as shown in Figure 2.

The wheels are thus pressed against a suitable ink ribbon which makes an impression on paper passing around the platen 32. The bushes 67 are free to slide on flats formed on the shaft 58 to a limited extent. Normally the spring plungers 75 operate to maintain the bushes 67 and shafts 68 in the relative position shown in Figure 1. When, however, the wheels 66 are moved to the left to make an impression, they are arrested as soon as they engage the platen 32 while the shaft 68 moves further to the left into the position shown in Figure 2. The pressure for effecting printing is supplied by the spring-plungers 75 acting through the setting racks 53 and the pinions 65. This arrangement is provided to prevent risk of the type being damaged during the actual printing operation. The rack 53 and pinion 65 provide a movement-increasing gearing so that the total linear movement of any type on the wheel 66 is greater than the total movement of the rack 53. Consequently, any error in the setting of the rack 53 will result in a magnified error in the setting of the wheel 66. In order to correct any such errors, justifying mechanism is provided for aligning the type wheels 66.

Each of the type wheels is provided, round one half of its periphery, with teeth 80, the gaps 81 between the teeth being each diametrically opposite one of the type. Justifying elements 82 are pivoted on a rod 83 and co-operate each with one of the type wheels 66. The rod 83 is supported by two plates 84 which are pivoted by means of adjustable eccentric pivots 85, one on each of the arms 70. The two plates are secured together by a cross-member 86 and tails 87 of the elements 82 are held against this cross-member by springs 88.

An arm 89 is secured to the assembly 84, 86 and a spring 90 is connected to this arm at one end and to one of the arms 70 at the other end. This spring rocks the assembly 84, 86 counter-clockwise so that an abutment 91 secured on the assembly engages an adjustable stop 92. The stop 92 is adjusted so that teeth 93 on top of the justifying elements 82 are just clear of the teeth 80 on the wheels 66.

After the wheels 66 have been positioned and immediately before the cam elements 77 engage and rock the arms 70 to effect printing, a pin 94 secured on a wheel 194 engages a cam surface 95 and rocks the assembly 84, 86 clockwise about the pivots 85. The justifying elements 82 will thus rock together so that the teeth 93 enter gaps 81 opposite them. The arrangement is such that the upper side of each tooth 93 tends to engage the underside of the tooth 80 which happens to be immediately above it (see Figure 5). After this engagement has taken place, the

corresponding element 82 rocks about its pivot 83 while the assembly 84, 86 continues its movement.

After this has occurred, the arms 70 are rocked about the pivots 71. As the arms 70 rock each setting rack 53 will also rock about its pivot 54. During this movement the rack 53 rises relatively to the pinion 65 and rotates the latter and the wheel 66 clockwise. During this clockwise movement of the wheel the element 82 is rocked by its spring 88 clockwise and its tooth 83 enters fully into the gap between two of the teeth 80. It will be noted that the upper surface of the teeth 80 is substantially radial to the wheel 66 so that the tooth will, by engaging the surface, prevent further rotation of the wheel 66.

The clockwise movement of the wheel 66 which is a consequence of the arrangement shown is thus made use of to ensure that the tooth 83 shall be properly seated in one of the gaps between the teeth 80. If, after the wheel 66 has been finally located, there is any tendency for it still to rotate clockwise, this is taken care of by a slight downward movement of the rack 23.

The shaft 18, through gearing 96 and 97, drives a vertical shaft 98 which, through gearing 99, drives a shaft 100. This shaft operates known hammer-actuating mechanism for the numerical section of the printing mechanism. This hammer-actuating mechanism need not be described. The shaft 110, through gearing 101, drives a gear-wheel 102 which is rotatable on a shaft 103. The gear-wheel 102 can be coupled to the shaft 103 by a one-revolution clutch 104 which is engaged on the energization of a magnet PCM. The shaft 103 drives the wheels 78 and 194 of the alphabetical section. It will be recalled that these wheels bring about the actual printing by the type-wheels 66. The magnet PCM is energized at the proper time in each cycle in which alphabetical printing is required in any suitable manner, not shown herein. In such cycles as the printing mechanism is required to operate without the alphabetical section printing, no circuit is completed through the magnet PCM so that the clutch 104 remains disengaged and the shaft 103 is not driven. Thus, the magnet PCM would not be energized during a total printing cycle.

Referring now to Figure 4, there will now be described the manner in which the magnets RPM and FPM are energized under the control of the cards. Each card is fed downwardly from a magazine, first past a row of upper brushes UB and then, one cycle later, past a row of lower brushes LB. For this purpose card feeding mechanism of conventional construction is employed such as shown in the previously mentioned U. S. patent. At the moment when the "X" holes in a card are passing the upper brushes, cam contacts 110 close so that if there is an "X" hole in the card a circuit will be completed through the upper brush reading the column containing that hole, normally closed contacts 111a, one winding X of a double-wound relay, the contacts 110 and upper card lever contacts UCL which are closed in a known manner as long as a card is passing the upper brushes. The relay X is thus energized and closes its contacts X1 so as to complete a circuit extending through its holding winding Xh and cam contacts 112. These contacts remain closed until the zero holes on the same card pass the lower brushes. The relay winding Xh thus remains 70

energized for the same period and holds contacts X2 closed until the same time.

When the rack 41 (Figure 1) has moved sufficiently to the left to bring its tooth X opposite the nose of the pawl 49, cam contacts 113 close to complete a circuit through the print magnet FPM, the contacts X2 and the contacts 113. The magnet FPM then arrests the type-bar in the "X" position. This occurs while the card in question is passing the lower brushes.

As the card passes the lower brushes, a circuit is completed through the lowermost hole in the column in question, the corresponding lower brush and the magnet RPM. If there is a hole in one of the positions "0" to "9" the magnet RPM will be energized and will arrest the associated rack 23 in its corresponding position. If there is no hole in one of these two positions, the rack will move until arrested by the stop 52. Thus, by the "zero" time in the cycle in which the card passes the lower brushes, both the racks will have been positioned.

If there is no "X" hole in a particular column, the circuit previously traced through the upper brushes and the relay winding X will not be completed. Immediately after the "X" holes have passed the upper brushes, cam contacts 114 close momentarily to energize the operating coil 111 of a relay which includes the contacts 111a. When this relay is energized, the contacts 111a are opened and contacts 111b are closed, connecting relay coil Y to the upper brushes. As the "Y" holes pass the upper brushes, cam contacts 115 close so that if there is a "Y" hole in the particular column in question, a circuit will be completed through this hole, the appropriate upper brush, the contacts 111b, the relay coil Y, the cam contacts 115 and the contacts UCL. The coil Y closes its contacts Y1 to energize a holding coil Yh and also closes contacts Y2. The coil Yh is held energized by the contacts 112 until the "zero" time in the next cycle. When the "Y" tooth on the rack is opposite the nose of the pawl 49 (Figure 1), cam contacts 116 close to energize the magnet FPM through the contacts Y2. The rack 41 will thus be arrested in the "Y" position.

If there is neither an "X" nor a "Y" hole in a particular column, no circuits will be completed through the upper brush reading that column and the magnet FPM will not be energized. The rack 41 will then move to the position shown in Figure 2.

At the end of a cycle cam contacts 117 close to energize a relatching coil 118. The contacts 111a and 111b are normally latched with the contacts 111a closed. The function of the coil 111 is to unlatch them at the appropriate time so that they reverse their condition. The coil 118 operates to relatch them in their normal condition.

Assume that the column of a card has a single hole in the "9" position. When this card passes the upper brushes no circuit is completed through the upper brush reading the column in question. When the card passes the lower brushes, a circuit is completed through the hole and the magnet RPM so that the pawl 30 (Figure 1) engages the uppermost tooth in the rack 23. Initially the type-wheels are positioned with the gap between the M and Y type opposite the platen. The slight upward movement of the rack 23 rotates the type-wheel until the "9" type is approximately opposite the platen. Towards the end of the cycle the cross head 38

(Figure 1) moves to the left and the particular rack 41 in question moves until arrested by the stop 51. This will result in the type wheel being rotated through slightly more than three type spaces so as to bring the "9" type just 5 above the printing line, as shown in Figure 5. The justifying elements 82 are then rocked and the tooth 93 on one of them engages in the gap 81 opposite the "9" tooth. The arms 70 are then rocked so as to move the type-wheels against 10 the platen and during this movement the wheel turns slightly clockwise until the tooth 93 seats itself fully in the notch 81 as shown in Figure 6.

The "9" type is then in the "printing" position and an impression is taken from it. If 15 there had been an "X" hole as well as a "9" hole, the rack 41 would have been arrested after one step of movement and would have turned the type-wheel through slightly more than one type space so as to bring the "M" type just 20 above the printing line. During the printing movement of the type-wheels this type would have been accurately positioned. In the same way, a "Y" and a "9" hole result in the "Y" 25 type being brought to the printing position.

When the type bar 23 is arrested in the position shown in Figure 2 as the result of there being a "zero" hole in the card, the operation is similar except that the rack 23 will still be rising when the rack 41 moves to the left. Thus, for 30 a short time the movement of the type-wheel will be the result of the joint movement of the two racks.

If there is no hole in one of the positions "0" to "9" the rack 23 rises to its highest position 35 and either the type "A" or the type "Z" or the type "." will be selected for printing in accordance with the position in which the rack 41 is arrested. The " ." type is selected if both the racks move to their full strokes. This type is 40 provided since the type wheel will move until some part of it engages the platen, and serves to prevent an impression being made from the top and bottom of the two adjacent types. The result of providing this type is that the words 45 printed will be separated by full-stops and all blank spaces in a line of letters will be filled in with dots.

While there has been shown and described and pointed out the fundamental novel features of 50 the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a printing machine, a pair of type setting bars, means for adjusting said bars, a bell crank operated by one of said bars, a differential link with one end pivoted on the other of said bars and at the other end connected to said bell crank, a rack pivoted on said link and moved a 65 distance which is the resultant of the combined movement of the bars, a type carrier operated by said rack, a platen, and means for impressing the type against the platen. 60

2. In a printing machine, a pair of type setting bars, means for adjusting said bars differentially, a bell crank one end of which is pivotally connected to one of said bars, a differential link carrying a fulcrum stud, said link being pivoted at one end on the other of said bars 70

75

and at the other end carrying a pin fitting in a slot in said bell crank, said slot being normally inclined to compensate for the arcuate movement of said stud, a rack pivoted on said stud, 5 a type carrier operated by said rack, and means for printing from said type carrier on record material.

3. In an alphabet printing machine, a digit bar adjusted differentially according to a digit entry, 10 a zoning bar adjusted differentially according to one of three possible zoning entries, a link with connections to both bars so that at one end it is lifted by the digit bar and at the other end it is lifted by the zoning bar, a type carrier with 15 a series of spaced type, a rack for setting said carrier in a position to print from a selected one of said type, said rack being operated by said link and pivoted thereon near the connection to the digit bar so that one step of movement of 20 the digit bar causes three type spaces of movement on the carrier, and each step of movement of the zoning bar causes a movement of a single type space on the carrier, and means for printing from the type carrier on record material.
- 25 4. In a printing machine controlled by record cards, a pair of type setting bars, means under control of the cards for setting said bars, a dif-

ferential link with connections to said bars so arranged that one end of the link is moved by one bar and the other end of the link is moved by the other bar, a type carrier, a rack for moving said type carrier to printing position, said rack being connected to said link to be moved by the combined action of both bars, and means for printing from said type carrier on record material.

5. In an alphabet printing machine controlled 10 by record cards perforated with regular digit perforations and special zoning perforations, a digit bar, means under control of the digit perforations for adjusting said digit bar, a zoning bar, means under control of said zoning perforations for adjusting said zoning bar, a differential link with connections to said bars so that each end is moved by one of said bars, a type carrier with a series of type, a carrier operating rack pivoted on said link at such a point that one step 20 of movement caused by the digit bar moves the carrier through a number of type spaces greater by one than the number of type space movements caused by adjustment of said zoning bar, and means for printing from said type carrier on record material.

HAROLD HALL KEEN.
